(57) **CLAIM**

The ornamental design for a building control module, as shown and described.

DESCRIPTION

FIG. 1 is a perspective view of a building control module; FIG. 2 is a front elevation view of the building control module of FIG. 1;

FIG. 3 is a left side view of the building control module of FIG. 1;

FIG. 4 is a right side view of the building control module of FIG. 1;

FIG. 5 is a top plan view of the building control module of FIG. 1;

FIG. 6 is a bottom plan view of the building control module of FIG. 1;

FIG. 7 is a perspective view of the building control module of FIG. 1 with top and bottom covers removed;

FIG. 8 is a perspective view of another building control module;

FIG. 9 is a front elevation view of the building control module of FIG. 8;

FIG. 10 is a left side view of the building control module of FIG. 8;

FIG. 11 is a right side view of the building control module of FIG. 8;

FIG. 12 is a top plan view of the building control module of FIG. 8;

FIG. 13 is a bottom plan view of the building control module of FIG. 8; and,

FIG. 14 is a perspective view of the building control module of FIG. 8 with top and bottom covers removed.

In the drawings, the claimed design is defined by the shaded surfaces; broken lines immediately adjacent shaded surfaces represent boundaries of the claim and form no part thereof; all other broken lines depict unclaimed environmental subject matter and form no part of the claim.
